CYLINDER HEAD OF INTERNAL-
COMBUSTION ENGINES

Robert Kelman Crowe and Harvey Charles Mansell, Bristol, England, assignors to The Bristol Aeroplane Company Limited, Bristol, England, a British company

Application October 8, 1941, Serial No. 414,204
In Great Britain March 1, 1940

3 Claims. (Cl. 123—171)

This invention relates to cylinder-heads of internal-combustion engines of the air-cooled sleeve-valve type. The cylinder head of a sleeve-valve engine comprises a cylindrical portion extending into the cylinder and separated from it by a space in which the sleeve rotates and reciprocates, and a circular base-portion extending across the combustion space. The base-portion thus lies at the bottom of a deep recess in the head and, in view of the difficulty of forming cooling fins on the outer surface of the base, it has already been proposed to manufacture the two portions separately and secure them together by screwing one part into the other after the fins have been formed on the base.

In view of the high duty of modern internal-combustion engines, and particularly of aero-engines, one of the most serious problems is to provide adequate cooling for the cylinder-head, and particularly for the base-portion in heads of the kind described above, and it is an object of the present invention to provide an improved joint between the two portions of the head so as to give improved conductivity of heat from the base to the cylindrical portion, and also to give a satisfactorily strong joint.

According to the invention, the two portions of a cylinder-head of an internal-combustion engine of the kind described are formed with complementary surfaces which interengage by an interference fit. The two portions preferably interengage by complementary cylindrical flanges fitted one within the other and, according to another feature of the invention, the engaging surfaces are tapered in such sense as to interlock with one another.

In the accompanying drawings:

Figure 1 is a sectional elevation on the line 1—1 of Figure 2 of a cylinder-head in accordance with the present invention, and

Figure 2 is a plan of Figure 1, with certain parts omitted.

The cylinder-head comprises a cylindrical portion 10 having a radial shoulder 11 which engages the end of the cylinder. The portion 10 fits within the cylinder and provides an annular space around it to accommodate a sleeve-valve. This portion 10 is formed with cooling fins 12, 13 which may be arranged in any desired manner to give an effective dissipation of heat.

In the particular construction shown, the fins 12 extend upwards from the upper surface 14 of the head and downwards in the cylindrical portion 10, and are connected to a more or less cylindrical wall or baffle 15 which partially sur-

rounds the space in the middle of the head in which the sparking-plugs are located by holes 30. A similar construction is provided for the fins 13 which are associated with a baffle 16. With this arrangement, cooling is effected by a flow of air along the top of the cylinder-head from the right-hand side in Figure 1, inside the engine-cowling 17, and the baffle 15 causes this stream to flow downwards to the lower part of the head, whence some passes up the central space around the sparking-plugs to cool them and the remainder passes up between the baffle 16 and the adjacent wall around the fins 13. A suitable baffle 18 is provided between the upper margin of the fins 12, 13 and the cowling to ensure this direction of flow of the air and baffles 31 (Figure 2) assist in this direction of the air-flow.

The base-portion of the cylinder-head comprises a circular plate 19 formed with an upstanding flange or rim 20, and it has formed on it cooling fins 21 which extend parallel with one another across the upper surface of the plate 19, as shown most clearly in Figure 2. The air-stream above-mentioned flows between these fins 21 in its passage through the head.

The cylindrical portion 10 of the head terminates in a flat annular face 22 which abuts the shoulder surrounding the flange 20, and the internal surface 23 of the part 10 is of complementary shape to the external surface of the flange 20.

The base-portion 19, therefore, is engaged within the cylindrical portion 10 and its engagement is by an interference fit. In the case of a cylinder-head about 6 inches in diameter, the interference is from 0.001 to 0.004 inch, and the assemblage of the parts is effected by a shrinking-on process. This can be effected by heating the portion 10 to, say 250° C., or the necessary temperature-difference can be obtained by cooling the base-portion 19 and heating the cylindrical portion 20.

In order to increase the strength of the joint between the two parts, the internal surface 23 of the part 10 may diverge upwardly in a conical form, the angle of the taper being, for example, 1° so that when assembled the parts are interlocked by a kind of dove-tailed joint whereby separation of the two parts is positively prevented.

It is customary to provide sealing-rings in the cylinder-head to engage the inner surface of the sleeve-valve, and it is an important feature of this invention that the groove or grooves 24

for these rings are each formed wholly in the base-portion 19 or in the cylindrical portion 20, and are not formed in or on the abutting faces 22, since it is important that the maximum contact-area should be obtained at the face 22 to ensure the maximum conductivity for heat from the base 19 to the cylindrical part 10. This feature of maximum conductivity of heat is further ensured by the intimate contact obtained at the surface 23 by the interference fit between the parts, and the total result is that the heat in the hottest portion of the head, namely, the base 19, is adequately conducted away to the cooling fins 21 and to the cylindrical body-portion 10 and thence to the cooling fins 12, 13 from which it is dissipated in the stream of cooling air.

We claim:

1. In an air-cooled internal-combustion engine, a recessed cylinder head comprising a circular base formed integrally with closely spaced cooling fins extending parallel to one another and an upstanding peripheral flange, a cylindrical body-portion interengaged tightly with the flange and formed with radially disposed integral internal cooling fins extending from the top end of the body-portion and baffle means engaging the inner ends of the radially disposed fins to direct air flowing over the top of the cylinder head into and out of the interior of the body portion.
2. In an air-cooled internal-combustion engine, a recessed cylinder head comprising a cir-

cular base formed integrally with closely spaced cooling fins extending parallel to one another from side to side of the base and also formed integrally with an upstanding peripheral flange surrounding the fins, and a cylindrical body portion interengaged with the flange on the base with an interference fit and formed integrally with two similar sets of internal cooling fins extending approximately radially of the body portion and extending from the top end thereof and also with a baffle plate for each set which plate is integral with and unites to inner edges of the fins in its set.

3. In an air-cooled internal-combustion engine, a recessed cylinder head comprising a cylindrical body-portion formed with two sets of radially disposed cooling fins integral with its inner surface, united at their inner ends by a baffle plate, terminating short at one end of the body and extending beyond the other end thereof, and a circular base formed integrally with an upstanding peripheral flange on its top surface and with closely spaced parallel cooling fins extending across its top surface, the flange on which base is engaged in the first mentioned end of the body with an interference fit in such a manner that the two sets of fins on the body overlie the ends of the fins on the base and the fins on the base extend into the body.
